UNITED STATES PATENT OFFICE.

WILLIAM S. PIERCE, OF FRANKLIN, PENNSYLVANIA, ASSIGNOR TO PIERCE PACKER & SUPPLY CO., OF FRANKLIN, PENNSYLVANIA, A CORPORATION OF PENNSYLVANIA.

DEVICE FOR USE IN OIL AND GAS WELLS.

1,273,663.

Specification of Letters Patent.

Patented July 23, 1918.

Application filed May 29, 1917. Serial No. 171,658.

To all whom it may concern:

Be it known that I, WILLIAM S. PIERCE, a citizen of the United States, residing at Franklin, in the county of Venango and State of Pennsylvania, have invented certain new and useful Improvements in Devices for Use in Oil and Gas Wells; and I do hereby declare the following to be a full, clear, and exact description of the invention, such as will enable others skilled in the art to which it appertains to make and use the same.

The present invention relates to improvements in devices for use in oil and gas wells, and the primary object thereof is to provide a well casing that is arranged to be lowered into the well independent of the working barrel and pumping apparatus; and which casing will be equipped with the usual packer to prevent water from above descending into the oil and gas field, and with interior valves for preventing flow of fluid from the inside of the casing outwardly to the oil field, whereby the working barrel and pumping apparatus may be entirely withdrawn from the well casing without the danger of water from above being allowed, after getting into said casing, to pass therefrom into the oil and gas field.

By making the well casing and working barrel, together with the pumping apparatus, entirely separate, I am enabled to remove at any time this working barrel and pumping apparatus for the purpose of repairing, cleaning, etc.

A further object of my present invention resides in providing a chamber in the well casing about the standing valve in which the sand, dirt, or other foreign particles, which may be admitted through the standing valve, with the fluid with which they are held in suspension, may settle.

It is a still further object of my present invention to provide above the packer and surrounding the upper part of the well casing, a chamber to receive fragments of crumbled rock and earth which may have been dislodged from the well wall above.

In the accompanying drawings forming a part of this application, and in which similar reference symbols indicate corresponding parts in the several views:

Figure 1 is a vertical sectional view of an

improved apparatus constructed in accordance with my present invention, and illustrated in operative position within a well.

Fig. 2 is an enlarged longitudinal sectional view, partly in elevation, of the working barrel and pumping apparatus; and

Fig. 3 is an enlarged sectional view of the lower portion of the well casing and standing valve.

Referring more particularly to the drawings, in which one embodiment of my present invention is illustrated, 1 designates the lower and 2 the next adjacent upper sections of the well casing, which are shown to be joined together by the coupling 3. Above this coupling 3 is a packer 4 of any suitable character which, when in place, will prevent water or other foreign material which may be present in the well above from passing down into the oil and gas field, which is indicated generally at 5.

The lowermost section 1 of the well casing is received at its lower end into a reducing coupling 6, which carries a shoe or pipe 7 having perforations 8 therein through which the fluid matter in the oil field 5 may pass. The reducing coupling 6 is threaded internally, as shown at 9 in Fig. 3, to receive the lower end of a tube 10 on which the standing valve 11 is supported. This tube 10 extends to a relatively great height above the reducing coupling 6, and is of considerably less diameter than the diameter of the well casing 1, providing, with the latter, an annular chamber 12 in which the sand, dirt, or other foreign particles suspended in the oil, may settle; as otherwise such foreign material might have a tendency to adhere to the standing valve 11 or to its seat, and prevent the accurate seating of such standing valve.

The upper end of the uppermost section 2 of the well casing extends above the packer 4, and provides thereabout a chamber 31 provided to receive fragments of crumbled rock and earth that may have released themselves from the sides of the well wall. The upper end of the well casing 2 is open and threaded to receive a head 13 having a beveled upper end 14. This beveled end 14 forms a seat for the packing 15 held in the complementally beveled lower end of a coupling piece 16. The coupling

piece 16 is carried on the lower end of the tubing 17, through which the oil is pumped to the surface and through which reciprocates the sucker rod 18. The coupling piece 5 16 carries a working barrel 19 which extends down within the well casing sections 2 and 1, and when positioned therein has its lower end just above the standing valve 11. The working barrel 19 is of less exterior diameter than the interior diameter 10 of the well casing 1, 2, for the purpose of providing an annular chamber 20 through which the gas from the oil and gas field 5 is allowed to escape to the gas relief pipe 21, in a manner hereinafter more fully explained.

The lower end of this barrel 19 carries a collar 22 for the purpose of spacing the barrel from the casing. In the bottom of 20 the barrel 19 is a stationary valve 23 which opens upwardly to admit the oil freely from the casing section 1 when the pressure within the barrel 19 is less than that in the well casing; but which automatically closes to 25 trap the fluid in the barrel 19 and compel it to be elevated through the tubing 17 and to the surface of the well on the further operation of the pump plunger, as will be readily understood by those skilled in the 30 art. This pump plunger is indicated at 24 and may be of any suitable type, it carrying the check valve 25. The plunger 24 is reciprocated vertically in the barrel 19 by the sucker rod 18.

35 The adjacent ends of the sections 1 and 2 forming the well casing, do not meet in the coupling 3, but are separated to permit the entrance of the gas to the annular chamber 20. The coupling 3 is provided at this point 40 with an opening 26 which communicates with a valve chamber 27 having located therein a check valve 28. This check valve 28 opens upwardly by the action of the gas in ascending, and permits such gas to freely 45 pass into the valve chamber 27 and from there through the opening 26 and into the annular gas chamber 20. The valve 28, however, will prevent back flow, as it will automatically seat when the pressure above 50 is greater than that below.

In the coupling piece 16 is a passage 29 which has its lower end disposed at the top of the annular chamber 20 for the purpose of receiving the gas ascending therein and 55 delivering it to the gas relief pipe 21 which carries the gas to the surface.

The operation of the present apparatus is substantially as follows:

The well casing consisting of any number 60 of sections, as, for instance, the two sections 1 and 2 shown in the accompanying drawings, is lowered into the well until it arrives at its proper position with respect to the gas and oil field 5; whereupon the 65 packer 4, which is of any suitable type, may

be set so that upper water bearing strata are entirely cut off from the oil and gas field 5 below said packer.

After the well casing and packer have been properly located and set, the oil tubing 70 17, gas piping 21, together with the coupling piece 16 and suspended working barrel 19, are lowered into the well and the barrel 19 is received within the well casing, in its final position, taking up the location 75 shown in Fig. 1; and the coupling piece 16 will, when finally located, rest in the position shown in Fig. 1 with its beveled lower end engaging the upper beveled end of the head 13, the packing 15 being pressed firmly 80 against the head 13 by the weight of the tubing 17 above, and forming a tight joint to prevent the escape of gas from the annular chamber 20 or the entrance of water or other foreign matter from the exterior 85 into said annular chamber 20. After being in the position as shown in Fig. 1, gas from the field 5 may freely pass up through the valve 28 into the annular chamber 20 and through the passage 29 to the piping 21, by 90 which it will be conveyed to the surface.

The oil will flow in through the perforations 8 in the pipe 7 and up through the tubing 10 and through the standing valve 11 into the lower section 1 of the well casing. 95 Here it will give up its suspended matter, which will be deposited in the annular chamber 12. It is to be understood that the standing valve 11 will automatically open to admit this oil at all times when the pressure within the well casing is lower than that in the oil field, which change in pressure is constantly being brought about by the operation of the plunger 24, as will be understood.

On the up-stroke of the plunger 24 the valve 25 will, of course, be seated, and a suction will be created in the lower part of the barrel 19, which will have the effect of unseating the stationary valve 23 and causing 110 an in-rush of the oil from the well casing into said barrel. On the down-stroke of the plunger 24 the stationary valve 23 will be held by the pressure to its seat, and the oil will, in the usual manner, be forced through the moving valve 25 and up through the plunger 24 into the upper part of the barrel 19, from which it will be delivered to the oil tubing 17 on subsequent strokes of the plunger 24.

From time to time as it becomes necessary or desirable to clean the working barrel 19 or to replace any of the valves 23, 25, or appurtenant parts, the same may be withdrawn upwardly through the well without necessitating the removal of the casing and packer 4, and without allowing any of the water or foreign matter in the well above to descend down into the oil field which would be destructive. When the barrel 19, 130

coupling piece 16, tubing 17, and gas piping 21 are removed upwardly through the well, water from strata above may descend into the chamber 31 about the well casing, but 5 it will be prevented by the packer 4 from getting down into the field 5 on the exterior of the well casing. Water from above may also find its way into the interior of the well casing through the open mouth at the 10 head 13, but such water will not be permitted to flow from the casing into the oil field by reason of the standing valve 11 which operates in one direction only.

After the working barrel and pumping 15 apparatus have been cleaned and parts renewed, the same may be replaced in the well, as shown in Fig. 1, and upon subsequent operation of the plunger 24 the water which has found its way into the well casing will 20 be elevated up through the working barrel and oil tubing 17, and will be thus driven out of the well without having the opportunity to get into the oil and gas field 5.

In a similar manner, any water or foreign 25 matter that may descend into the annular gas passage 20, will be unable to get into the oil and gas field 5 through the valve chamber 27, because of the check valve 28 therein preventing any back flow.

30 My present invention forms a very effective apparatus for protecting the oil and gas field from the damage occasioned by water or other foreign material, and at the same time admits of the ready removal of the 35 working parts of the device to permit cleaning and removal of the parts.

I wish it distinctly understood that the packer 4 and packing 15, as shown in the drawing, are merely for purposes of illustrating one form which these devices may 40 take; I reserve the right to employ other styles of packers and packings, and to place the same in different relations to the other parts of my invention than those disclosed herein; and if desirable, I may omit such 45 packers or packings entirely, as, for instance, in the case where the amount of water admitted would be very slight, such water may be permitted to flow into the open upper end 50 of the chamber 20, whence it will get down into the pump chamber and be pumped out with the oil. In no case, however, will the water be allowed to get into the oil field 5.

It will be understood, moreover, that I do 55 not desire to be confined to the construction of the pumping apparatus as I have illustrated it, nor to the particular manner in which it is fitted to my invention, as it is apparent that other types of such apparatus 60 may equally well be employed and be attached in various ways. Furthermore, the valves 11 and 28, as well as those shown in the pumping apparatus, are indicated as ball check valves only to give expression to one 65 construction of which the invention is

susceptible, and other equivalent valves may be substituted.

It is obvious that those skilled in the art may vary the details of construction and arrangements of parts without departing from 70 the spirit of my invention, and therefore I do not wish to be limited to such features except as may be required by the claims.

I claim—

1. In a device of the character described, 75 the combination of a short length of casing adapted to be placed in the lower part of a well and having an open upper end, a packer carried by said casing for preventing foreign matter from upper strata from passing to 80 the oil and gas field, a pumping apparatus adapted to be removably fitted in said casing and being withdrawable from the well independent thereof, said pumping apparatus adapted to divide said casing to provide 85 separate oil and gas chambers, means carried by said pumping apparatus for normally closing the open end of said casing, means for carrying off the gas from said gas chamber separately from the oil, and means 90 for permitting the free entrance of oil and gas from the oil and gas field respectively to said oil and gas chambers but preventing back flow or the passage of foreign matter from the interior of said casing to said oil 95 and gas field when the pumping apparatus is removed, substantially as described.

2. In a device of the character described, the combination of a casing adapted to be fitted in a well and providing in the lower 100 part thereof an oil chamber, a standing valve in said oil chamber, a pumping barrel of smaller diameter than said casing adapted to be fitted therein and providing therewith a gas chamber, means carried by said pumping barrel for separating said oil and gas chambers, a gas check valve for admitting gas from the gas field to said gas chamber, an oil pipe for conveying the oil to the surface from said pumping barrel, and a gas 105 conduit for conveying away separately the gas from said gas chamber, substantially as described.

3. In a device of the character described, the combination of a casing of relatively 115 short length fitted in the lower part of a well, a packer surrounding said casing and preventing the passage of foreign matter from upper strata from getting into the oil and gas field said casing projecting upwardly beyond said packer and providing with the well walls a chamber to receive foreign matter held from passage by said packer, a pumping apparatus removably fitted in said casing and withdrawable from 120 the well independently thereof, means carried by said pumping apparatus for dividing the casing into oil and gas chambers, a stand pipe of lesser diameter than said casing fitted in said oil chamber and having 125 130

open communication with the oil field, said pipe providing with the casing a chamber for the deposit of the foreign matter held in suspension in the oil, a stand valve held on the upper end of said pipe, a gas check valve for admitting gas from the gas field to said gas chamber, means for separately carrying off the gas from said gas chamber, and independent means for conveying the oil to the surface from said oil chamber, substantially as described.

4. In a device of the character described, the combination of a casing of relatively short length having an open upper end and 15 being fitted in the lower part of a well, a packer surrounding said casing, a head secured to the upper open end of said casing, a pumping apparatus removably fitted in said casing, a coupling piece carried by said 20 pumping apparatus and adapted to rest on said head and close the upper end of said casing, oil and gas chambers in said casing, a standing valve in said oil chamber, and a gas check valve for admitting gas to the gas 25 chamber, substantially as described.

5. In a device of the character described, the combination of a casing having an open upper end fitted in the lower part of a well, a packer surrounding said casing, a head 30 having a beveled upper end held on the upper end of said casing, a removable pumping apparatus fitted within said casing, a coupling piece carried with said pumping apparatus and having a beveled lower end 35 fitting the beveled upper end of said head whereby to close the upper end of said casing, a packing confined between the beveled ends of said coupling piece and head, oil and gas chambers in said casing, a standing 40 valve in said oil chamber, a gas check valve for admitting gas to said gas chamber, piping for conveying the oil to the surface, said coupling piece having a passage communicating with said gas chamber, and separate piping connected to said passage for 45 conveying off the gas, substantially as described.

6. In a device of the character described, the combination of a casing fitted in the 50 lower part of a well and having an open upper end, a head carried on the upper end of said casing, a removable pumping apparatus fitted in said casing, a coupling piece connected to said pumping apparatus and 55 adapted to rest upon said head to close the upper end of said casing, oil and gas chambers in said casing, a stand pipe in said oil chamber in open communication with the oil field and providing with the casing a chamber 60 for the deposit of suspended matter in the oil, a standing valve held on the upper end of said pipe, a gas check valve for admitting gas to said gas chamber, and means

for conveying off the oil and gas separately, substantially as described.

7. In a device of the character described, the combination of a casing adapted to be fitted in the lower part of a well and having an open upper end, a packer fitted about said casing, the casing extending upwardly 70 beyond said packer and forming with the well walls a chamber to receive foreign matter, a head carried on the open upper end of said casing, a pumping apparatus removably fitted in said casing, a coupling piece carried 75 by said pumping apparatus and adapted to rest on said head to close the upper end of said casing, oil and gas chambers in said casing, a stand pipe in said oil chamber having open communication with the oil 80 field and forming with the casing walls a chamber for the deposit of foreign matter suspended in the oil, a stand valve held on said pipe, a check valve for admitting gas from the gas field to said gas chamber, and 85 separate oil and gas piping for removing the oil and gas respectively from said oil and gas chambers, substantially as described.

8. In a device of the character described, a well casing having an open upper end, a 90 packer carried by the outside of said well casing for preventing foreign matter from passing to the oil and gas field, oil and gas chambers in said casing, valves for admitting the oil and gas to said chambers, but 95 preventing back flow therefrom to the oil and gas field, a head at the open upper end of said casing, a coupling piece removably resting on said head, a packing between said coupling piece and head, a working barrel 100 carried by said coupling piece and extending down within said casing, and a pumping device operating in said barrel, substantially as described.

9. A device of the character described including adjacent casing sections adapted to be fitted in the lower part of a well, a coupling uniting the ends of said sections, the ends being separated in said coupling, a working barrel removably fitted in said casing, a pump plunger operating in said working barrel, means carried by said working barrel for partitioning the casing to provide oil and gas chambers, a standing valve in said oil chamber, a gas check valve carried 115 by said coupling and adapted to admit gas between the ends of said casing sections, a head on the upper end of the casing, a coupling piece connected to said barrel and resting on said head, and means connected to 120 said coupling piece for separately conveying off the oil and gas, substantially as described.

In testimony whereof, I affix my signature.

WILLIAM S. PIERCE.
